UNITED STATES PATENT OFFICE

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA

PRECOOLER FOR VACUUM PUMPS

Application filed October 18, 1930. Serial No. 489,501.

This invention relates to vacuum pumps and more particularly to a precooler associated with the pump for cooling the air or gases prior to their entrance into the pump for maintaining proper temperature of the fluid pumped to insure efficient operation of the pump and prevent the re-evaporation of water or other fluids which have been previously condensed, during their passage to the pump.

More particularly, the present invention comprises a precooler of the surface type through which the air or gas to be pumped travels in a counter current or sinuous path between and about a plurality of tubes through which cooling water is circulated and a precooler which is attached directly to the head end of the pump. The cooling water circulating system of the precooler has direct communication with the water cooling system of the pump, thereby providing a combined precooler and pump construction which is simple, efficient, will occupy a relatively small space as well as one which may be manufactured at a relatively small cost.

With these and other objects in view, as may appear from the accompanying specification, the invention consists of various features of construction and combination of parts, which will be first described in connection with the accompanying drawings, showing a precooler for vacuum pumps of the preferred form embodying the invention, and the features forming the invention will be specifically pointed out in the claims.

In the drawings:

Fig. 1 is a vertical section through the precooler showing it attached to a vacuum pump which pump is shown partly in section.

Fig. 2 is a side elevation of an alternate or modified form of the invention.

Referring more particularly to the drawings, 1 indicates a vacuum pump of approved construction embodying the cylinder 2 in which the piston 3 reciprocates. The cylinder 2 is water jacketed as shown at 4 and the water jacket section 5 at the head end of the rotative dry vacuum pump 1 has its outer side or end closed by the tube sheet or tube head 6 of the precooler structure 7. The precooler 7

is of the surface type embodying a plurality of tubes 8 extending between the tube head 6 and the outer tube head 9 and through which the cooling water circulates from the water jacket section 5 into the water box 10 for the purpose of cooling air or gas passing through the shell 11 of the precooler.

The water box or chamber 10 is shown in Fig. 1 of the drawings as connected to the water jacket 4 of the pump 1 by a pipe 12 and the cooling water first enters the water jacket structure of the pump in the section 5 through the water inlet pipe 14 and circulates about through the water jacket and through the tubes 8 for efficiently cooling the pump as well as cooling the air or gas passing through the cooler.

The air or gas enters the precooler through the suction or inlet opening 15 and is guided in a sinuous path through the shell 11 of the cooler by baffles 16, leaving the cooler through the outlet 17.

The outlet 17 is connected by a suitable connection 18 with the suction space 19 of the vacuum pump 1 so that the air or gas will be drawn through the precooler into the suction space 9 through the suction valve 20 of the pump and discharged from the pump through the discharge valve 21.

As will be noted by particular reference to the drawings, the precooler is attached directly to the pump body, the water jacket section 5 serving as one of the water boxes of the precooler, thereby providing a compact relatively simple construction which will effectively cool the air or gas to the proper temperature prior to its entrance into the vacuum for assuring maximum efficiency in the operation of this pump.

The modified construction shown in Fig. 2 of the drawings, is in its major details, similar to the form shown in Fig. 1. The cylinder 30 of the vacuum pump 31 has the precooler 32 directly attached to the head end thereof and it is to be understood that a section of the water jacket of the cylinder 30 serves as one of the water boxes of the precooler 32 in the same manner as that disclosed in the form illustrated in Fig. 1.

In contradistinction to the form shown in

Fig. 1, this modified form has the cooling water inlet 33 connected to the outer water jacket 34, so that the cooling water first passes through the precooler and thence into the section 35 of the water jacket of the cylinder 30, passing into the remaining portions of the water jacket through a suitable connection 36, also the air or gas suction inlet 37 of the precooler opens or enters into the precooler nearest the end adjacent to the pump cylinder 30 and the air and gas travels in a sinuous path through the precooler away from the pump 30 as shown by the dotted arrows, and out of the precooler at the end remote from the pump 31. The air or gas returns to the pump 31 through the suitable connection 38.

It will be understood that the invention is not to be limited to the specific construction or arrangement of parts shown but that they may be widely modified within the invention defined by the claims.

What is claimed is:

1. The combination, of a vacuum pump having a water jacket, a precooler of the surface type embodying circulating cooling water tubes for cooling air or gas prior to its entrance into the pump, said precooler having water chambers at the ends of the tubes, one of said water chambers being a part of the water jacket of said pump.

2. The combination, of a vacuum pump having a water jacket, a precooler of the surface type embodying circulating cooling water tubes for cooling air or gas prior to its entrance into the pump, said precooler having water chambers at the ends of the tubes, one of said water chambers being a part of the water jacket of said pump, the other of said water chambers having communication with the water jacket to permit circulation of water through the precooler and water jacket.

3. The combination, of a vacuum pump having a water jacket, a precooler of the surface type attached directly to said pump, said precooler comprising water chambers and tubes for circulating cooling water to cool air or gas prior to its entrance into the pump, one of the water chambers of said precooler forming a part of the water jacket of said pump, means connecting the air or gas outlet of the precooler to the suction of said pump, and baffles arranged staggeredly in the precooler for directing air or gas therethrough in a sinuous path.

4. The combination, of a vacuum pump having a water jacket, a precooler of the surface type attached directly to said pump, said precooler comprising water chambers and tubes for circulating cooling water to cool air or gas prior to its entrance into the pump, one of the water chambers of said precooler forming a part of the water jacket of said pump, means connecting the air or gas outlet of the

precooler to the suction of said pump, and baffles arranged staggeredly in the precooler for directing air or gas therethrough in a sinuous path, the other water chamber of said precooler having communication with the pump water jacket to permit circulation of water through the precooler and water jacket. 70

5. The combination, of a vacuum pump having a water jacket, a precooler of the surface type attached directly to said pump, said precooler comprising water chambers and tubes for circulating cooling water to cool air or gas prior to its entrance into the pump, one of the water chambers of said precooler forming a part of the water jacket of said pump, 75 means connecting the air or gas outlet of the precooler to the suction of said pump, and baffles arranged staggeredly in the precooler for directing air or gas therethrough in a sinuous path, the other water chamber of said precooler having communication with the pump water jacket to permit circulation of water through the precooler and water jacket, 80 and a cooling water inlet communicating with one of said water chambers. 90

6. The combination, of a vacuum pump having a water jacket, a precooler of the surface type embodying circulating cooling water tubes for cooling air or gas prior to its entrance into the pump, said precooler having 95 water chambers at the ends of the tubes, one of said water chambers being a part of the water jacket of said pump, the other of said water boxes having communication with the water jacket to permit circulation of water 100 through the precooler and water jacket, and a cooling water inlet communicating with the water chamber which forms a part of the water jacket of the pump.

7. The combination of a vacuum pump including a cylinder having a water jacket thereabout, a precooler including a shell attached directly to said cylinder, said precooler including cooling water circulating tubes and water chambers, one of said water chambers forming a part of the water jacket of the cylinder, a cooling water inlet communicating with the water chamber remote from said cylinder whereby cooling water will first enter and pass through the precooler and then into the water jacket of the pump. 110 115

8. The combination of a vacuum pump including a cylinder having a water jacket thereabout, a precooler including a shell attached directly to said cylinder, said precooler including cooling water circulating tubes and water chambers, one of said water chambers forming a part of the water jacket of the cylinder, a cooling water inlet 120 communicating with the water chamber remote from said cylinder whereby cooling water will first enter and pass through the precooler and then into the water jacket of the pump, said precooler having an air or gas in- 125 130

let adjacent to the pump cylinder and provided with baffles to guide the air or gas in a sinuous path through the cooler away from the pump cylinder and means connecting it 5 through the precooler to the suction of the pump.

In testimony whereof I affix my signature
JOHN F. GRACE.
